DESIGN FOR A BED LAMP

Louis W. Robinson, Kansas City, Mo.

Application February 18, 1946, Serial No. 126,639

Term of patent 3½ years

(Cl. D48—20)

To all whom it may concern:

Be it known that I, Louis W. Robinson, a citizen of the United States, residing at Kansas City, in the county of Jackson and State of Missouri, have invented a new, original, and ornamental Design for a Bed Lamp, of which the following is a specification, reference being had to the accompanying drawing, forming a part thereof.

Fig. 1 is a perspective view of the bed lamp showing my new design.

Fig. 2 is an edge elevational view thereof with a portion broken away for convenience of illustration; and

Fig. 3 is a rear elevational view thereof with a portion broken away for convenience of illustration.

I claim:

The ornamental design for a bed lamp, as shown.

LOUIS W. ROBINSON.
